DESIGN FOR A FOUNTAIN PEN

Samuel E. Fry, Winnetka, Ill., assignor to Montgomery Ward & Co., Incorporated, Chicago, Ill., a corporation of Illinois

Application June 16, 1937, Serial No. 69,866

Term of patent 7 years

To all whom it may concern:

Be it known that I, Samuel E. Fry, a citizen of the United States, residing at Winnetka, in the county of Cook and State of Illinois, have invented a new, original, and ornamental Design for Fountain Pens, of which the following is a specification; reference being had to the accompanying drawing, forming a part thereof.

In the drawing,

Fig. 1 is a side elevation of a fountain pen showing my new design, the cap being in closed position on the body of the pen, as when the pen is not required for use;

Fig. 2 is a similar view, the viewpoint being at right angles to that of Fig. 1;

Fig. 3 is a top end view;

Fig. 4 is a bottom end view; and

Fig. 5 is a perspective view with the cap applied to the upper end of the body of the pen as when the latter is in use.

I claim:

The ornamental design for a fountain pen, as shown and described.

SAMUEL E. FRY.
